UNLOADING APRON AND DRAIN TROUGH FOR WASHERS

Filed Feb. 21, 1930

UNITED STATES PATENT OFFICE

ALONZO D. STALEY, OF CINCINNATI, OHIO, ASSIGNOR TO THE AMERICAN LAUNDRY MACHINERY COMPANY, OF CINCINNATI, OHIO, A CORPORATION OF OHIO

UNLOADING APRON AND DRAIN TROUGH FOR WASHERS

Application filed February 21, 1930. Serial No. 430,274.

My invention relates to washing machines. It relates, particularly, to an unloading apron and drain trough for a washing machine of the type in which is used a cleaning fluid such as gasoline or like cleaning fluids as detergents. However, the invention may be applied to any washing machine of the type shown regardless of the fluid used in the washing operation.

- 10 Heretofore, few washing machines of the type shown have been equipped with hinged unloading aprons and, in those machines equipped with an apron, the construction has generally been such that it was necessary to 15 rotate the apron over the lower edge of the tub or casing door opening to place it in operative relation with the door opening of the drum or cylinder. With this construction, the apron has formed an obstruction 20 preventing complete closing of the outer tub or casing door in the event of an explosion or fire and is, therefore, undesirable. Further, previous unloading aprons have not provided 25 means for returning to the washing operation any detergent liquid which drains from the work while it is being withdrawn from the machine.

One object of my invention is to provide an unloading apron which is entirely contained 30 within the outer casing and is so arranged and constructed that there will be no obstruction to prevent complete closing of the outside tub casing door.

Another object of my invention is to provide 35 a drain trough in conjunction with the unloading apron whereby the fluid draining from the articles being removed from the washer will be returned to the machine.

Other objects of my invention will appear 40 in the following detailed description and one embodiment thereof may be seen in the accompanying drawing wherein like references designate corresponding parts, and wherein:

Fig. 1 is an end elevation with parts broken 45 away showing a washing machine equipped with my invention.

Fig. 2 is a detail elevation showing a portion 50 of the front of the washing machine, parts being broken away to more clearly show the construction.

Fig. 3 is a sectional view on the line 3—3 of Fig. 2, showing the unloading apron and drain trough with the unloading apron in operative relation with the drum.

Fig. 4 is a view similar to Fig. 3 but 55 showing the outer tub or casing door in closed position.

Referring to the drawing, I have shown a washing machine embodying a tub or outer casing 1 adapted to contain a fluid and an inner drum or casing 2 that is perforated in the usual manner and is mounted in bearings supported by the end frame 3 of the casing 1 and adapted to rotate therein.

The inner and outer casings 1 and 2 are each 60 provided with a door, the outer tub or casing being provided with a hinged door 5 and the inner drum or casing being provided with a hinged door 6. As shown in Fig. 1, the doors 5 and 6 of the respective inner and outer casings 65 may assume registering relation with each other or may be moved to such relation and, when the doors are in such relation, the lower edge 7 of the outer casing door opening 70 is in a radial line with the lower edge 8 of the cylinder door opening.

A portion of the outer tub or casing which forms the lower edge 7 of the outer casing door opening is flared outwardly as at 9 (see Figs. 1, 3 and 4) and an angle iron 10 is secured 80 to such outwardly flaring portion to provide an abutment against which the lower edge of the outside casing door 5 may rest when closed.

On the inner side of the outer casing and 85 adjacent the flared portion 9 thereof, a perforated member 11 is secured by means of rivets 12 or other suitable fastening means and embodies a vertically extending portion 14 and a horizontally extending portion 15, which, with the wall 9, form a triangular shaped chamber 9a adapted to receive detergent, which drains to it through the wall 15, and deliver it into the machine.

Extending inwardly from the horizontal portion 15 of the member 11 and secured to such member is an angle iron 16 which extends longitudinally of the casing along the entire length thereof, and pivotally mounted 95 100

on the edge of such angle iron, as at 17, is a metal plate or apron 18.

In the operation of this device, the doors 5 and 6 of the inner and outer casings are registered and moved to open position. Then, the plate or apron 18 is moved about its pivot until its free edge rests in a groove 19 in the stave 20 of the inner casing, as in Fig. 3, whereupon the articles within the inner casing may be drawn over the plate or apron 18, angle iron 16 and horizontal portion 15 of the member 11 and removed from the machine, the fluid draining from the articles being returned to the interior of the machine by reason of the chamber hereinbefore described, and the angular position of the members 16 and 18 of the machine. Then, other articles may be placed in the drum, the plate or apron 18 being rotated to the position shown in Fig. 1, the doors 5 and 6 closed, and the machine operated in the usual manner. In this position the apron lies in a recess 10a of the tub frame below the abutment surface 10. 25 A latching means 21 is provided for securely holding the outer tub or casing door against the angle iron 10 which forms a rest therefor. Such latching means is of the lever type and is so constructed that it will automatically latch the door in position when such door is closed.

In Fig. 4 of the drawing, the unloading apron is shown in operative position with respect to the perforated drum or cylinder 2 with the door 6 thereof partially closed and resting on the upper surface of the apron. Also, as shown in this figure, the outer tub or case door 5 is in closed and latched position, which is not interfered with by the apron or inner shell or casing door. This possibility of closing the outer tub or case door completely when the unloading apron is in operative position is particularly advantageous in the event of an explosion or fire within the machine, or other emergency conditions.

It will be seen that I have provided a device embodying numerous novel and advantageous features. For instance, I have provided an unloading apron for washing machines of such nature that the unloading apron is disposed at all times within the outer shell or casing and in such position that it will never interfere with the complete closing of the outer case door irrespective of whether or not it is in operative bridging relation with the inner drum. This is clearly shown in Figs. 1 and 4. Further, the unloading apron is of such nature as to form a ground connection between the inner and outer casings, thereby reducing fire hazard.

Another advantageous feature resides in the fact that a drain trough is provided in conjunction with the unloading apron and is of such nature that fluid draining from

the articles being drawn over the unloading apron will be returned to the inside of the washing machine. Thus I have provided a means for preventing the accumulation of washing fluid outside of the machine.

What I claim is:

1. Apparatus of the class described comprising, in combination with a washing machine including a tub having an opening therein and a door closure therefor and a rotatable drum within said tub having a door opening movable into registry with said tub opening and a door closure therefor, a hinged unloading apron mounted within the interior of said tub adjacent the lower edge of the door opening and adapted to be moved from an inoperative position to bridge the gap between said tub and said drum, and means permitting fluid flowing from treated goods being removed from said drum to drain back into said tub including a perforated member having a top portion forming substantially a continuation of said unloading apron when said apron is in bridging position.

2. Apparatus of the class described comprising, in combination with a washing machine including a tub having an opening therein and a door closure therefor and a rotatable drum within said tub having a door opening movable into registry with said tub opening and a door closure therefor, a hinged unloading apron mounted within the interior of said tub adjacent the lower edge of the door opening and adapted to be moved from an inoperative position to bridge the gap between said tub and said drum, and a drain trough within said tub consisting of a perforated member having a top portion forming substantially a continuation of said unloading apron and a side portion cooperating with the inner wall of said tub to form the trough.

3. Apparatus of the class described comprising, in combination with a washing machine including a tub having an opening therein and a door closure therefor and a rotatable drum within said tub having a door opening movable into registry with said tub opening and a door closure therefor, a hinged unloading apron mounted within the interior of said tub adjacent the lower edge of the door opening and adapted to be moved from an inoperative position to bridge the gap between said tub and said drum, and means permitting fluid flowing from treated goods being removed from said drum to drain back into said tub including a perforated member having a top portion forming substantially a continuation of said unloading apron when said apron is in bridging position, said apron and trough being in a position as not to interfere at any time with the closure of said tub door, and an automatic operating latching means for said stationary drum door.

4. Apparatus of the class described com-

prising, in combination with a washing machine including a tub having an opening therein and a door closure therefor, and a rotatable drum within said tub having a door opening movable into registry with said tub opening and a door closure therefor, an unloading apron mounted on a fixed pivot within the interior of said tub adjacent the lower edge of the door opening and having 5 two positions, said apron being movable from an inoperative position wherein it extends horizontally away from the door opening of said drum to an operative position wherein it extends horizontally toward the door opening 10 in said drum to bridge the gap between said tub and said drum and to present a substantially smooth surface across which goods may be drawn in removal from said drum, and said apron being positioned relative to 15 the lower edge of said tub door opening whereby to permit complete closure of the tub door when said apron is in bridging position.

In testimony whereof I hereby affix my
25 signature.

ALONZO D. STALEY.
